UNITED STATES PATENT OFFICE.

MARION MALLORY, OF WICHITA, KANSAS.

SPARK-PLUG.

1,304,341.

Specification of Letters Patent.

Patented May 20, 1919.

Application filed March 7, 1918. Serial No. 220,987.

To all whom it may concern:

Be it known that I, MARION MALLORY, a citizen of the United States, residing at Wichita, in the county of Sedgwick and State of Kansas, have invented certain new and useful Improvements in Spark-Plugs; and I do declare the following to be a full, clear, and exact description of the invention, such as will enable others skilled in the art 10 to which it appertains to make and use the same.

My invention has for its object to provide a spark plug whose insulator is so constructed as to render short circuiting practically 15 impossible unless the insulator is damaged.

With the foregoing general object in view, the invention resides in the novel features of construction to be hereinafter fully described and claimed, the descriptive matter 20 being supplemented by the accompanying drawing which forms a part of this specification and in which a longitudinal section of part of the insulator in elevation, is shown.

In the drawing above briefly described, 25 the numeral 1 designates a cylindrical metal shell externally threaded at its lower end as seen at 2 and by preference provided with a gasket 3 for fluid tight engagement with the engine cylinder, the upper end of the shell 30 being formed with a head 4 of a shape to be engaged by a wrench, said head having in its upper end a socket 5 into which the bore of the shell opens.

An insulator 6 is received throughout substantially half of its length in the shell 1 in slightly spaced relation to the latter, the intermediate portion of said insulator having an annular shoulder 7 received in the socket 5 and preferably tapered inwardly on its 40 upper side as shown. A gasket 8 is interposed between the shoulder 7 and the bottom of the socket 5 and a retaining ring 9 bears against the upper side of the shoulder and is threaded into said socket to secure the insulator in place.

A central electrode 10 passes through the insulator 6 and coats with a ground electrode 11 carried by the shell 1, the upper end of said electrode 10 having a nut or the like 50 12 for the attachment of the current conducting wire, while the lower portion of this

electrode extends into a bore 13 formed in and opening through the lower end of the insulator 6.

In order for a plug of the type so far set 55 forth to short circuit, provided the insulator remains intact, it is necessary for the current to flow from the shell 1 down the exterior of the insulator, around the lower edge of the latter, and upwardly along the wall of the 60 bore 13 to the central electrode 10, and in order to decrease the liability of such short circuiting, I lengthen the travel of the current by forming superimposed preferably 65 V-shaped grooves 14 in the wall of the bore 13. By this construction, instead of taking a straight course up the wall of the bore, the current must zig-zag with the result that its travel is greatly increased. Before the current has time to travel over this long course 70 and short circuit, it will jump across the gap between the electrodes 10 and 11 and fire the charge in the cylinder.

From the foregoing, taken in connection with the accompanying drawing, it will be 75 obvious that although my invention is of extremely simple and inexpensive nature, it will be highly efficient for preventing short circuiting, and since probably the best results are obtained from the several details 80 shown and described, these features are preferably employed, but within the scope of the invention as claimed, numerous minor changes may well be made. Also, I wish it understood that any suitable material may 85 be employed in the manufacture of the device and that it may be made in any of the well known standard sizes or in additional sizes should occasion so demand.

I claim:

A spark plug comprising a vertically elongated, hollow, cylindrical shell open and screw-threaded at its lower end and provided at its upper end with a socket, a one-piece, vertically elongated insulator having 95 between its ends an integral head secured in said socket, said insulator depending from said head into said shell, substantially to the lower end of the latter and in spaced relation with the shell wall, said insulator having a longitudinal bore leading from its lower end wall into said head, the wall of 100

said bore having superimposed V-shaped grooves giving thereto a zig-zag formation free of horizontal surfaces, an electrode secured in said insulator and extending 5 through said bore, and a ground electrode extending from said shell.

In testimony whereof I have hereunto set

my hand in the presence of two subscribing witnesses.

MARION MALLORY.
